[57] **CLAIM**

The ornamental design for a hand-held flying toy, as shown.

DESCRIPTION

FIG. 1 is a perspective view of a hand held flying toy showing my new design;

FIG. 2 is a left side elevational view thereof;

FIG. 3 is a top plain view thereof, the string and rod removed for ease of illustration;

FIG. 4 is a right side elevational view of FIG. 3;

FIG. 5 is a front elevational view of FIG. 3;

FIG. 6 is a right side elevational view of a second embodiment of FIG. 1, the left side being a mirror image; and, FIG. 7 is a right side elevational view of a third embodiment of FIG. 1, the left side being a mirror image.
